UNITED STATES PATENT OFFICE.

HERMAN G. ESSMAN, OF NEW YORK, N. Y.

HAND SIGNAL LIGHT.

Application filed October 24, 1925. Serial No. 64,620.

This invention relates generally to a hand operated signal lamp. It is the object of this invention to provide a signal lamp which may be held on the operator's hand such as by attachment to one of his fingers, palm, or otherwise, and which may be operated by the movements of the hand or fingers. The specific embodiment of the invention disclosed and described herein, has special application to manual signaling by automobile operators. It will become obvious that the lamp has many other applications and uses for various signaling and illuminating purposes, such as by ushers in theaters and the like.

In the drawings—

Figure 1 shows a front view of the preferred embodiment of the present invention. Fig. 2 shows an end view of the invention. Fig. 3 shows a longitudinal sectional view. Fig. 4 shows the back of the casing. Figs. 5 and 6 show details of the construction.

The casing of the lamp consists of the body portion 10 and the cover 11. The body portion 10 which is preferably stamped out of an integral piece of sheet metal, comprises an oblong portion 12 and a circular portion 13, the two portions being connected by a constricted narrow portion 14. The circular portion 13 is provided with slots 15 and 16 on its periphery, as shown in Fig. 2. The back face of the body portion 10 is provided with two sockets 17 and 18 for the reception of the ends of the holding ring 19. The sockets 17 and 18 are preferably integral with the body of the casing and stamped out from the back of the casing.

The cover 11 is shaped in such a manner as to conform to the shape of the body 10 of the casing. The cover 11 is also provided with an oblong portion 20 and a circular portion 22. The circular portion of the cover is provided with a circular opening 23 which may be of any size desired and which is in the preferred embodiment of the invention, of a diameter that approximates the diameter of the circular portion 21.

The body of the casing 10 is provided with a notch 24 which cooperates with a lug 25 on the cover 11 for the purpose of assembling the two parts and holding the same in closed position as shown in Figs. 2 and 3. The lower edge of the cover is provided with a teat 26 which cooperates with an aperture 27 in the lower edge of the

body of the casing. The assembly of the two parts of the casing is accomplished by inserting the lug 25 into the notch 24 and then depressing the cover over the body of the casing until 26 enters the aperture 27. The lower edge of the cover 11 is also provided with two projections 28 and 29 which facilitate the removal of the cover from the body of the casing.

In the constricted portion 14 of the body of the casing, is a device which is designed to serve as a socket for receiving the electric signaling bulb. This socket 30 is shown in detail in Fig. 6 of the drawing. It is formed to the shape shown, out of a piece of sheet metal. It is provided with two plates 31 and 32 which are disposed in substantially parallel planes and are connected together by means of the back plate 33. The plate 32 is provided with downwardly extending wings 34 and 35 which are shaped to conform with the inner sides of the constricted portion 14 of the body of the casing. The socket 30 is held in position by the frictional engagement of the wings 34 and 35 against the walls of the casing. The plates 31 and 32 are provided with registering apertures 39 and 40 which are designed to receive the threaded lamp base 36 of the lamp 37. The center contact 38 of the lamp projects beyond the aperture 40 into the oblong portion of the casing.

Within the oblong portion of the casing is placed a small electric cell 41 which is provided with two contact terminals 42 and 43. The contact terminal 42 is longer than the contact terminal 43 and extends to a point in contact with the center contact 38 and is always in contact therewith. The contact terminal 43 is normally out of contact with the casing of the lamp. The resilient switch contact strip 44 is riveted to the inner face of the circular portion of the body of the casing 10 by means of the rivet 45. A knob 46 is attached to the strip 44 and projects outwardly of the casing through the aperture 47 in the casing. The contact strip 44 passes under the plates 31 and 32 through notches 48 and 49 provided therefor, and has a bent portion 50 which projects into proximity with the terminal strip 43. It will be seen that by depressing the knob 46 the resilient contact strip 44 is depressed in such a manner that its free end 50 comes in contact with the terminal strip 43 and thereby the circuit of the electric

5 bulb is completed and the electric bulb is illuminated. When the pressure on the knob 46 is released, the circuit is broken. A transparent device 50 shaped in the manner shown in Fig. 5 and made preferably of celluloid or other similar material, is placed in the circular portion 51 of the face of the element 50 is painted red for signaling purposes.

10 In order to prevent accidental closing of the circuit, a locking device is provided which under normal conditions and when the signal lamp is not intended for use, will 15 prevent the accidental closing of the circuit. The locking device comprises a strip 52 which is pivotally riveted to the back of the casing at 53. Its free end 55 is designed to be inserted into the space between 20 the knob 46 and the back of the casing. The free end 55 is provided with a notch 54 which engages the shaft of the knob and the other end of the strip 53 which projects 25 beyond the casing to facilitate the operation thereof, is serrated.

30 The signal lamp is held on the back of the operator's hand by mounting the ring 19 on one of the fingers of the operator's hand. Normally with the operator's hand 35 on the driver's wheel, the hand and fingers are spaced from the operating knob 46 and the circuit of the electric bulb is open. When, however, the operator extends his arm for signalling purposes, his hand is straightened and thereby comes in contact with the operating knob 46 and depresses it, whereby the contact strip 44 is depressed

35 into contact with the terminal strip 43 and the signaling device is automatically illuminated. The ring 19 serves as a fulcrum or 40 as a reaction member for the finger so as to facilitate the application of pressure to the operative knob. It is obvious that in place of the ring 19 which is designed to be slipped over the operator's finger, a handle 45 large enough to slip over the operator's palm may be used without altering the operation of the lamp.

40 Having described my invention, I do not wish to limit myself to the specific embodiment disclosed herein. Many modifications of the invention disclosed herein and the uses disclosed herein, will appear to any persons skilled in the art.

45 What is claimed is:

50 1. A hand signal lamp comprising a casing having a substantially oblong chamber, a substantially circular chamber and a constricted portion between said chambers, a light supporting element disposed in said 55 constricted portion formed of sheet metal and comprising two spaced integrally connected plates having registering apertures, and wings having frictional engagement 60 with the walls of the casing.

65 2. A hand signal lamp comprising a casing having a chamber for the reception of a cell, another chamber for the light, and a light supporting element removably mounted within said casing between said chambers and having frictional engagement with the sides of the casing and comprising two 70 spaced connected plates.
